WHEEL

Donald J. Reid, Pleasant Ridge, Mich., assignor to
Kelsey-Hayes Company, Romulus, Mich.

Filed Feb. 12, 1970, Ser. No. 21,414

Term of patent 14 years

Int. Cl. D12—16

U.S. Cl. D14—30

FIG. 1 is a front elevational view of a wheel embodying my design;

FIG. 2 is a sectional view thereof taken along the line II—II of FIG. 1;

FIG. 3 is a blown up view of that portion of the wheel of FIG. 1 encircled by the dot dash line indicated by the arrow III;

FIG. 4 is a fragmentary sectional view taken generally along the line IV—IV of FIG. 3; and

FIG. 5 is a perspective view of the wheel of FIG. 1.

I claim:

The ornamental design for a wheel, substantially as shown and described.
